15 Claims. (Cl. 178—53.1)

1

This invention relates to a telegraph system in which the message characters are transmitted by means of permuted marking and spacing pulses separated by intervals, and more particularly to improved distributor apparatus for applying such signals in proper order to a receiving device.

In telegraph communication systems for certain types of services, it is highly important that the receiving equipment be compact and light in weight, and such equipment should not require the use of rotary receiving distributors for applying the received signals to a recorder or other receiving device. For example, in radio communication between airports and airplanes the matter of size, weight and simplicity of the receiving apparatus required in the planes is of great importance. In telegraph printer distributor systems in which rotatable distributors are required, this means that distributor driving motors must be provided in the aircraft, together with a special source of power therefor, such that the motors will run at a constant speed substantially in synchronism with the incoming signals, and furthermore means must be provided for synchronizing and orienting such distributor apparatus with respect to the received signals. If relay distributors of the type heretofore known were employed in lieu of rotary distributors for receiving the incoming signals, such distributors would necessarily have groups of counting chain relays and the disadvantage that for the reception of each character signal pulse there is required the operate time of the counting circuit plus the operate time of the switching circuit plus the length of the pulse received, and thus such distributors would reduce the rate at which incoming signals may be received.

In accordance with the instant invention a receiving distributor system is provided in which the switching circuit for distributing the signal pulses is immediately set in motion to prepare for the reception of the next signal pulse and the registration of the instant signal pulse on the storage equipment is started at the same time, these two operations commencing substantially simultaneously. An extremely short interval only is required after the termination of each pulse to allow the receiving circuit to release before the next signal pulse can be received, since the circuit for receiving the succeeding signal pulse is prepared at the time that the instant pulse is being received, while at the same time there is no possibility of two signals being registered for a single pulse received.

One of the objects of the invention is a re-

ceiving distributor system in which the disadvantages of both the rotary type distributor and relay type distributor heretofore proposed are obviated, and in which the signals are properly received regardless of any variation in the rate at which they are transmitted.

Another object of the invention is an improved telegraph system in which the message characters may be transmitted at a high rate of speed by means of marking and spacing pulses separated by slight intervals or no-current conditions, and in which the speed at which such signals may be transmitted is not reduced by any appreciable time lag in the receiving relay distributor apparatus.

Any additional object is a receiving distributor apparatus in which no rotating parts are required and in which synchronization of the receiving apparatus with respect to the transmitting apparatus need be effected only at infrequent intervals.

Still another object of the invention is a receiving distributor in which circuits for the reception of a succeeding signal pulse are prepared simultaneously with the reception of an immediately preceding or instant signal pulse, for distributing the pulses to the proper elements of the receiving device.

A further object is a receiving distributor in which the time lag in the distributor transfer relay circuits is reduced so that it is practically negligible.

These and other objects of the invention will be apparent from the following detailed description, taken in connection with the accompanying drawings of two embodiments thereof, in which:

Fig. 1 illustrates transmitting and receiving distributor apparatus, adapted for line wire transmission, constructed in accordance with the principles of the instant invention;

Fig. 2 illustrates diagrammatically a radio transmitting and receiving system embodying the principles of the invention, the figure showing receiving apparatus adapted to be employed with the receiving circuit of Fig. 1 with certain modifications therein; and

Fig. 3 shows one of the modifications required in the circuit of Fig. 1 to adapt the receiving circuit for radio reception.

Referring now to Fig. 1 of the drawings, the upper portion thereof shows transmitting apparatus which, in the embodiment illustrated, employs a tape transmitter TT, having transmitting contacts C which operate between marking con-

tacts M and spacing contacts S in known manner, depending upon the perforations in the tape, to transmit permutation code marking and spacing pulses. The marking contacts M are shown connected to a source of negative battery 1, and the spacing contacts S are connected to a source of positive battery 6, whereby the spacing pulses are positive in polarity and the marking pulses are negative in polarity, although it will be understood that the polarity of these pulses may be reversed if desired. The tape transmitter may be of any suitable type known in the art, for example, as illustrated in the Benjamin Patent No. 1,298,440, issued March 25, 1919. From the transmitting tongues or contacts C of the tape transmitter the polar marking and spacing pulses are applied to five transmitting segments of the segmented ring 10 of a transmitting distributor TD, the transmitting segments being separated by blank segments 12. This distributor is of the type employing a rotatable brush B which is controlled by a start magnet SM in known manner, the signals applied to the segments of ring 10 being transmitted as brush B revolves, through the brush to the solid transmitting ring 11 and thence over the telegraph line L. If desired, a combined tape transmitter and distributor embodying the foregoing elements may be employed, various of which are known in the art, and one of which is disclosed in the patent to Potts No. 2,057,111, issued October 13, 1936, except that the segmented ring of the transmitting distributor is modified by the interposition of the blank segments 12 to provide an open or no-marking condition which inserts short intervals between successive marking and spacing pulses. The operation of the distributor TD and also of the tape transmitter TT may be controlled in known manner, as by a tight tape switch TTS, which controls the circuit of the distributor start magnet SM. The tight tape switch is controlled by a loop of perforated tape T which is fed through the transmitter TT in known manner, the tape issuing either directly from a perforator or a storage supply of tape which is perforated in permutation code in accordance with the messages to be transmitted.

A source of negative battery 13 normally is connected, by means of contact elements 14, to the rest or stop segment S of the distributor, so that a marking signal normally is applied to the line L when the transmitter is at rest. Battery 13 also is applied, through switch contacts 15, and the contacts of the tight tape switch TTS to the start magnet SM whenever there is a sufficient length of tape t in the loop of the tight tape switch. It will be understood that when the loop of tape is sufficiently large, the tight tape switch contacts will be closed and the start magnet SM energized to release the distributor brush B for rotation.

The switch elements 14 and 15 also are controlled by a synchronizing cam 16 which is driven from a motor 17 at a predetermined rate of speed such that the high point of cam 16 will momentarily open contacts 14 and 15 at predetermined time intervals for synchronizing the transmitting and receiving apparatus in a manner hereinafter described. The motor 17 preferably is the same motor that drives the distributor brush B, and the cam 16 may be so geared that the contacts 14 and 15 will be opened momentarily after transmission of any desired number of characters, for example, after a hundred characters, the momentary opening of these contacts causing the trans-

mitter brush to come to rest on the stop segment S until the contacts are reclosed by continued rotation of the cam 16. In the form disclosed the transmitting distributor has five character transmitting segments for the transmission of a five-unit permutation code, although it will be understood that any other suitable code may be employed, for example, a six-unit code, in which case the number of segments will vary correspondingly.

The receiving distributor shown in Fig. 1 preferably is an electronic distributor in which the receiving end of the line L has two line relays 19 and 20, relay 19 being a non-polar type which operates on each marking and spacing signal and which controls the timing of the receiving circuit, whereas relay 20 is a polar relay that is biased in any suitable manner, as by a spring 18, so that its armature tends to remain in the spacing position shown. The relay armature is actuated to its lower or marking position whenever a marking signal is received. The polar relay 21 causes the marking pulses received to be stored on pickup relays PU1 to PU5 on which the intelligence code elements are temporarily stored, the energized ones of the pickup relays representing marking code elements and the deenergized ones of these relays representing the spacing code elements. The control circuit comprises switching relays 31 to 36 and associated grid-controlled gas-filled rectifiers 41 to 46, which preferably are thyratron tubes, one switching relay and one rectifier being employed for each unit of the code received and for the stop or rest pulse.

Relay 19 has an upper inner grounded armature 21 and an upper outer armature 22. The inner armature controls the circuit of a slow-acting relay 25, the winding of which is connected to a source of positive battery 26, the circuit being completed to the grounded armature 21 when relay 19 is energized. Armature 22 of relay 20 has a grounded condenser 23 connected thereto, and controls two circuits, as follows: When relay 19 is deenergized, the armature 22 closes a circuit comprising a resistance 24 and the condenser 23 in series in order to discharge the condenser when the relay is in its released position. When relay 19 is energized, its armature 22 closes a circuit from grounded condenser 23 to a conductor 27 for the purpose of preparing the respective transfer circuits for operation as the signal pulses are received. The relay 25 has an armature and make contact 28 which controls the supply of current from the source 26 to a conductor 29 that is common to the windings of the various transfer relays 31 to 36.

Each of the first five transfer relays 31 to 35 has an upper armature and break contact 40, a lower inner armature 37 which operates between break and make contacts, and a lower outer armature 38 which also operates between break and make contacts. The sixth transfer relay 36 also has an upper armature and break contact 40 like the preceding relays 31 to 35, but its lower armature structure is different in that it has a grounded armature 39 and break contact which control a release circuit for the relays PU1 to PU6. The armatures 37 of the relays 31 to 35 are connected in chain circuit relation with each other by means of conductors 51 to 54, and the armatures 38 of relays 31 to 35 are connected in chain circuit relation with each other by means of conductors 64 to 67. Each of the grid-controlled gas-filled rectifiers 41 to 46 has a biasing potentiometer or voltage divider 48 which

normally causes sufficient negative potential to be maintained on the grids of the tubes so as to block the tubes and prevent them from firing until the negative charges on the grids are reduced during the operation of the system, as hereinafter described, to cause successive firing of the tubes.

When the transmitting distributor apparatus is at rest and the distributor brush B is in the position shown, negative marking battery is applied from the source 13, through switch elements 14, rest segment S, brush B, transmitting ring 11 and line L to the winding of non-polar relay 19, and thence through the winding of polar relay 20 to ground. Relay 19, therefore, remains operated, and polar relay 20 also remains operated to its marking position so that its armature 60 rests against its lower contact. Since relay 19 is operated, its armatures 21 and 22 are energized. Armature 21 and its make contact holds relay 25 operated and thus positive battery is applied through its armature and make contact 28 and conductor 29 to the energizing windings of relays 31 to 36. Operated armature 22 of relay 19 maintains a circuit from the grounded condenser 23 through armature 22 and its make contact, conductor 27 and thence through the chain circuit which comprises the lower inner armatures 37 and break contact of transfer relays 31 to 35, the break contact of each of the relays being connected to the armature 37 of the immediately preceding relay of the group by means of conductors 51, 52, 53 and 54. At armature 37 and break contact of relay 31 the circuit continues over a conductor 55 to the grid bias circuit of the first rectifier tube 41.

When the amount of tape in the tape loop T decreases sufficiently so that the tight tape switch contacts close, the start magnet SM will be energized, thereby releasing the distributor brush B for rotation. As the brush leaves the rest or stop segment S, it passes onto the first dead segment 12, thereby momentarily applying an interval or no-current condition to the line L. Relays 19 and 20 are, therefore, deenergized and both release, although relay 25 remains energized at this time, since it is of the slow-release type. The distributor brush then passes onto the first code segment 1 of the distributor. Assuming, for example, that the first intelligence character to be transmitted by the code segments 1 to 5 of the transmitting distributor is the letter "A," the code elements of which are marking, marking, spacing, spacing, spacing. As brush B contacts the first code segment of ring 10, a marking pulse of negative polarity will, therefore, be transmitted over the line L. This causes the reenergization of relays 19 and 20, the armature 60 of the latter relay being actuated to its lower or marking position. The energization of relay 19 causes the grounded condenser 23 to be connected through armature 22 and its lower contact to conductor 27, the circuit continuing through armature 37 and break contact of relay 35, conductor 51, armature 37 and break contact of relay 34, conductor 52, armature 37 and break contact of relay 33, conductor 53, armature 37 and break contact of relay 32, conductor 54, armature 37 and break contact of relay 31, and conductor 55 to the grid biasing circuit of the tube 41. This, in effect, puts an instantaneous ground on the grid of the tube, which reduces the negative grid bias formerly maintained on the tube to an extent such that the tube fires. The instantaneous ground is removed as soon as

condenser 23 becomes charged, which is of the order of 2 milliseconds in time, but once the tube fires it remains in this condition until its plate circuit is open.

- 5 The operation of polar relay 20 to its marking position connects the grounded condenser 61 through armature 60 to conductor 63, this circuit continuing through the lower outer armature 38 and break contact of relay 35, conductor 64, armature 38 and break contact of relay 34, conductor 65, armature and break contact of 38 of relay 33, conductor 66, armature 38 and break contact of relay 32, conductor 67, armature 38 and break contact of relay 31, conductor 91, and through the operating winding of relay PU1 to negative battery, thereby operating relay PU1 by reason of the charging current for the condenser 61 passing through its winding. The lower inner armatures 83 of the relays PU1 to PU5 and 86 of PU6 are "preliminary make" armatures which engage their associated contacts, when these relays are energized, before the remaining armatures of the relays engage their contacts. Energization of relay PU1 causes its preliminary make armature 83 to engage its make contact, thereby locking the relay through conductor 84 and grounded armature 85 of relay PU6. Relay 31 started to operate as soon as tube 41 fired, but the preliminary make armature 83 of relay PU1 engaged its make contact before the armature 38 and break contact of relay 31 opened the energizing circuit of PU1. The operating circuit for relay 31 is from the anode or plate circuit of tube 41, through upper armature 40 and break contact of relay 32, conductor 58, winding of relay 31, conductor 29, armature 28 and make contact of operated relay 25 to positive battery 26, which is a source of plate battery for the Thyratron tubes.
- 40 The distributor brush B next leaves segment 1 of ring 10 and passes onto the second dead or blank segment 12 of the ring, thereby again momentarily opening the line circuit L, and relays 19 and 20 release. The next code marking segment 2 of distributor ring 10 has been marked with negative battery from the tape transmitter TT, and hence as the brush engages this segment a negative marking pulse again is applied to line L, and relays 19 and 20 reoperate. The operation of relay 19 causes the grounded condenser 23 to be connected to the chain circuit which includes conductor 27 and the armatures 37 of relays 35, 34, 33 and 32; from armature 37 of relay 32 the circuit continues through conductor 54, armature 37 and upper make contact of operated relay 31 and conductor 70 to the grid circuit of Thyratron tube 42. In the same manner as in the firing of tube 41, the condenser 23 applies a momentary ground to the grid of tube 42 so that the negative biasing potential thereon is reduced to a point such that the tube fires. The second storage relay PU2 operates from the grounded condenser 61 in the same manner that the first storage relay PU1 operated, the circuit continuing through the armature 60 and lower make contact of polar relay 20, conductor 63, armatures 38 and lower break contacts of relays 35, 34, 33 and 32, conductor 67, armature 38 and upper make contact of operated relay 31, conductor 92 and operating winding of PU2 to negative battery. The preliminary make armature 83 and contact of PU2 cause relay PU2 to lock up prior to the operation of the second transfer relay 32, this relay operating from the plate battery of the second Thyratron tube 42. Operation of relay 32 opens,
- 50
- 55
- 60
- 65
- 70
- 75

at its upper armature 40 and break contact, the anode circuit of the first Thyratron tube 41, causing the tube to become extinguished and the first transfer relay 31 to become deenergized. The energization of relay 32 prepares, at its operated armature 37 and upper make contact, a path to the grid circuit of the succeeding Thyratron tube 43. Operation of the lower outer armature 38 of relay 32 transfers the storage circuit from relay PU2 to PU3 over conductor 93.

As distributor brush B passes onto the next dead segment after the second code segment, relays 19 and 20 again are released. The third code segment of distributor ring 10 applies, when brush B traverses the same, positive spacing battery to the line L. This battery will operate relay 19, but relay 20 does not operate, since it is biased by spring 18 to its spacing position. Operation of relay 19 causes the grounded condenser 23 to be applied to the biasing circuit of Thyratron tube 43, thereby causing the tube to fire. Transfer relay 33 operates in the manner of the preceding relays 31 and 32, but storage relay PU3 is not energized, since relay 20 did not operate to apply the grounded condenser 61 to the operating circuit of the relay; therefore, relay PU3, which remains deenergized, represents a spacing element of the code pulses thus stored. Relay 33, upon operating, transfers the circuit of condenser 23 to the grid circuit of the succeeding Thyratron tube 44 in a manner heretofore described and also transfers the storage circuit to the relay PU4 over conductor 94.

As brush B of the distributor reaches the dead segment immediately following the third code segment, the line L is again opened and relay 19 restores. Similarly, as the brush traverses code segments 4 and 5 to which spacing polarity has been applied, the transfer relays 34 and 35 and their associated Thyratrons 44 and 45 successively operate, and storage relays PU4 and PU5 remain unoperated, thereby to store the spacing code elements therein.

At this time the code elements of the complete character, which in this case is the letter "A," have been set up on the storage relays PU1 to PU5. These relays may apply in any suitable manner the code elements stored therein to a desired receiving device, for example, a tape perforator or a telegraph printer of the multiplex type. Such a type of recorder is indicated at the bottom of Fig. 1 by five selecting or trip latch magnets 97, which devices may represent either the selecting magnets of a telegraph printer or the trip magnets of a perforator. The magnets are selectively energized from battery through their windings and thence through the lower armatures and make contacts 98 of the operated ones of the storage relays PU1 to PU5, thereby storing the five code elements of the signal in the receiving device.

After leaving segment 5 of ring 10, the distributor brush B traverses the last dead segment of the ring and then engages the rest segment S of the ring. The latter causes negative marking battery again to be applied to line L, which again operates relays 19 and 20. The operation of relay 19 causes the grounded condenser 23 to be applied, through the armature 37 and upper make contact of operated relay 35 and through conductor 75, to the grid circuit of the sixth Thyratron tube 46, reducing the negative potential on the grid of the tube to such value as to cause the tube to fire. The operation of the polar relay 20 to its marking position causes

grounded condenser 61 to be connected through conductor 63, armature 38 and upper make contact of operated relay 35, conductor 96 and the operating winding of relay PU6, to negative battery. The latter relay operates and locks up through its preliminary make armature 86 and associated contact, conductor 87 and grounded armature 39 and break contact of the sixth transfer relay 36. The holding circuit of relay PU6 also locks through conductor 82 and the operated armatures 80 of relays PU1 and PU2. The operation of relay PU6 transfers at its lower armature 85 and break contact, the ground from conductor 84 and transfers the ground through its make contact to a relay 99. This relay, when operated, closes, through its armature 100 and make contact, the operating circuit of a print magnet or punch magnet PM of a printer or perforator, as the case may be, whereby such a recorder will print the character or perforate the code elements thereof which were stored in relays PU1 to PU5 and applied to the relays or magnets 97 of the recorder.

Relay 36 operates through the upper armature 40 and break contact of relay 31, conductors 78 and 79 and the plate circuit of tube 46. The operation of relay 36 at its armature 40 opens the plate circuit of tube 46 and extinguishes the tube and releases transfer relay 35, which restores. The operation of relay 36 at its armature 39 also opens the locking circuit of relay PU6, and PU6 will restore.

The various elements of the receiving distributor are now in the same condition as they were at the beginning of the cycle of operations, that is, tube 46 is firing and relays 19 and 20 are operated. If the character "A" which was just received and stored was the last character of a message, the distributor brush B would remain on the rest segment S, and the relays and tubes of the circuit would remain in the same condition until a subsequent message is received. However, when a second character is transmitted immediately after the first character, the distributor brush B does not stop but continues through a second cycle of operation, in which case the operation of transfer relay 31 opens the plate circuit of tube 46 and extinguishes the tube and releases relay 36 which partially prepares a locking path for relay PU6. Subsequent characters of the message are received in the same manner.

It will be seen from the foregoing that the receiving distributor described is adapted to receive and distribute to the printer, perforator or other receiving device the signals of the permutation code at any rate that they may be transmitted, and that the speed of operation of the distributor elements at any time is determined solely by the speed at which the incoming signal pulses are received at such time, whereby the receiver is adapted to operate at any signal speed either constant or variable. It is thus not necessary to maintain a particular phase relation of the distributing apparatus with respect to the transmitting apparatus, and it is not necessary to synchronize or phase the distributor except at remote intervals, although it may be desirable to send a synchronizing signal as a precautionary measure at certain intervals, say of 100 characters or 200 characters. Whenever a synchronizing signal is transmitted by the cam 16, which at this time momentarily opens the contacts 14 and 15, it removes the marking battery from the stop or rest segment S and deener-

gizes the start magnet SM, and this causes the release of relays 19 and 20 in the receiver and also releases the slow-acting relay 25 so that the source of battery 26 is disconnected from the transfer relays and also from the plate circuits of the Thyratron tubes, whereby each of these elements is restored to its unoperated condition. After the cam 16 has caused contacts 14 and 15 to be reclosed, negative marking battery will again be applied to the line through the rest segment S and will cause operation of relays 19 and 20. The operation of relay 19 will again connect the grounded condenser 23 to the grid circuit of the first Thyratron tube 41 and momentarily reduce the negative potential thereon, but the tube will not fire at this time because slow-acting relay 25 has not had time to operate so as to apply the plate battery 26 to the Thyratron tubes. The instantaneous ground produced by the connection of condenser 23 to the first Thyratron tube will not maintain the reduced negative potential on the grid which again assumes such a negative value as to prevent firing of the tube before the plate battery supply for the tube is connected by the relay 25.

Fig. 2 shows how the system may be employed with radio communication, and it is especially suited for transmission from an air port or other ground station or Fix to aircraft within the control area of such a station. The receiving distributor circuit of Fig. 1, with certain modifications as hereinafter pointed out, is adapted to distribute the radio signals generally in the same manner as signals received from an incoming wire line. Referring to Fig. 2, there are shown a spacing tone generator and a marking tone generator for generating spacing and marking tone signals under the control of the tape transmitter TT2 and the transmitting distributor TD2. The tongues or contact springs C of TT2 are connected to five code segments 1 to 5 of the segmented ring 101, which are separated by blank segments. In addition to the code segments, the ring has a rest segment S, and a segment 103 for timing and to provide a pulse for energizing the punch solenoid of a perforator or the print magnet of a printer in the receiving circuit. The marking tone generator is connected by conductor 102 to the segment 103, and also to the marking contacts M of the tape transmitter. The spacing tone generator is connected to the spacing contacts S of the tape transmitter. The marking tone generator produces a suitable frequency, for example, 1000 cycles, for modulating the radio carrier when marking signals are transmitted and also when segment 103 transmits a signal. The spacing tone generator produces a suitable frequency, for example, 1500 cycles, for modulating the radio carrier when spacing signals are transmitted. The modulating frequencies applied to the segmented ring 101 are connected to the radio transmitter by means of a rotary distributor brush B and the solid ring 104 of TD2.

At the receiving end the signals are detected, and audiofrequency signals pass from the radio receiver, by means of a conductor 108, to an amplifier, and thence to audio band pass filters where the marking and spacing tone frequencies are separated. The spacing tone frequencies are rectified and applied to a relay 110, and the marking tone frequencies are rectified and applied to a relay 111. Relay 110 has an upper armature 114 operating between break and make contacts. The armature is connected to a

grounded condenser 116, and the break contact is connected to a grounded resistance 117. The lower grounded armature 115 and make contact of relay 110, and the grounded armature 123 and make contact of relay 111, control the energizing circuit of slow release relay 121. Relay 111 also has an upper armature 120 operating between break and make contacts. The armature is connected to a grounded condenser 127, and its break contact is connected to grounded resistance 126. The lower inner armature 122 operates between break and make contacts; the armature is connected to a grounded condenser 130, and its break contact is connected to a grounded resistance 131. The make contacts associated with armature 114 of relay 110 and armature 120 of relay 111 are connected by conductor 27, which extends to Fig. 1, for controlling the operation of the Thyratrons 41 to 46 and the transfer relays 31 to 36. The make contact associated with armature 122 of relay 111 is connected by conductor 63, which extends to Fig. 1, for controlling the operation of the storage or pickup relays PU1 to PU6. Slow release relay 121 has an inner armature 141 and a make contact which is connected by conductor 29, which extends to Fig. 1, for controlling the application of positive battery from source 26b to the windings of the transfer relays 31 to 34 and 36, and through their windings to the plate circuits of the associated Thyratrons. Relay 121 also has an outer armature 142 which is connected to a grounded condenser 144, and associated with the armature is a break contact that is connected by conductor 74 which extends to the grid of tube 45 in Fig. 1. Armature 142 also has a make contact which is connected to a grounded resistance 143. When the distributor of Fig. 1 is employed for radio reception, the circuit shown in Fig. 3 is substituted for the circuit contained within the broken-line rectangle A of Fig. 1 so that positive battery is connected to an inner armature 150 of the relay 35' shown in Fig. 3, instead of to the winding of this relay as shown in Fig. 1. Instead of having battery applied by means of conductor 29, the winding of relay 35' is permanently connected to a source of positive battery 26a. The armature 150 and make contact of the relay 35' connect the battery 26a to the windings of relays 31 to 34 and 36 in the same manner that armature 141 and its make contact, Fig. 2, connects battery 26b to the windings of these relays. The receiving distributor operates in response to spacing and marking radio signals applied to the distributor circuit by means of the relays 110 and 111, respectively, generally in the same manner as the line wire circuit of Fig. 1, with the following exceptions: Both the spacing and marking relays 110 and 111 control, through their armatures and make contacts 114 and 120, the operation of the Thyratrons 41 to 46 and transfer relays 31 to 36, whereas in the line wire circuit only the non-polar relay 19 and its armature and make contact 22 control these relays. The operation of relay 111 through its armature 122 and make contact corresponds to the operation of the polar relay 20 of Fig. 1 in controlling the pickup relays PU1 to PU6. Relay 121, by means of its armature 141 and make contact, holds positive battery on the windings of the transfer relays 31 to 36 in the same manner that the armature 28 and make contact of relay 25 hold positive battery on all of the relays 31 to 36.

When the transmission stops, relays 110 and 111 release and open the operating circuit of the slow release relay 121, which releases. When this occurs, two operations take place: At its contact 141 positive battery is removed from the windings of relays 31 to 34 and 36, and through armature 142 and its break contact the grounded condenser 144 supplies a momentary ground to the grid of Thyratron tube 45, Fig. 1, causing the tube to fire, in the event that the tube is not already in this condition. The firing of tube 45 causes the energization of relay 35', Fig. 3, which transfers the circuit from the inner make contacts associated with armatures 114 and 120 of relays 110 and 111, Fig. 2, over conductors 27 and 75, to the grid of Thyratron tube 46, whereby when the transmission of signals is resumed the first signal received will cause firing of tube 46.

When the distributor brush B of distributor TD2 is set into operation by the transmission of a message, the first segment contacted by the brush after it leaves the rest segment is segment 103, which causes a marking tone signal to be applied to the radio transmitter to modulate the carrier. The receipt of this marking signal by relay 111 of Fig. 2 causes the energization of the relay which, through its armature and make contact 120 and the grounded condenser 127, causes a pulse to be applied over conductor 27 and thence to the grid of tube 46 to cause the tube to fire. The next segment of ring 101 which is contacted by the brush B is a blank or no-current segment. The firing of tube 46 and operation of its associated transfer relay 36 opens the plate circuit of tube 45 which is extinguished and releases transfer relay 35', Fig. 3, thereby preparing the receiving circuit for the reception of the next character to be transmitted. The release of relay 35' switches the conductor 27 to the chain circuit comprising the inner armatures 37 and break contacts of transfer relays 31 to 35, and thence to the grid circuit of the first Thyratron tube 41 whereby, when the next momentary ground is applied to this circuit, the tube will fire.

When the brush B reaches the first code segment of ring 101, and assuming the letter "A" will be the first character of the message, a marking signal will be transmitted while brush B traverses the first code segment 1. This marking pulse will be received by the system of Fig. 2 and energizes the marking relay 111. This relay, through its armature 120 and make contact, causes the grounded condenser 127 to be connected, through conductor 27, to the grid circuit of the first Thyratron tube 41 and apply a momentary ground to its grid, thereby causing the tube to fire. As the brush B travels over the blank segment following code segment 1, relay 111 releases. Brush B next reaches the second code segment 2, causing a marking signal to be transmitted. This signal again causes the operation of relay 111 and applies momentary ground to the grid circuit of Thyratron tube 42. The operation of tube 42 causes deenergization of tube 41 and transfer relay 31 in the manner heretofore described with respect to the line wire circuit. Storage relays PU1 and PU2 will have been operated in the same manner as heretofore described.

When brush B passes to the third code segment 3 of ring 101, a spacing tone is transmitted, and this causes the operation of relay 110 at the receiver. This relay, through its armature 114 and make contact, causes a momentary ground to be

applied by condenser 116 to the grid circuit of Thyratron tube 43, causing the tube to fire. Pickup relay PU3, however, is not energized, thereby causing transmission of a spacing pulse to the perforator or printer. Similarly, as the brush B traverses code segments 4 and 5 of ring 101, spacing tones will be transmitted and received to cause the successive firing of Thyratron tubes 44 and 45. After leaving code segment 5, brush B again traverses the stop segment S, which causes tube 46 to fire and pickup relay PU6 to become energized, which releases pickup relays PU1 to PU5. Pickup relay PU6 remains energized until all the relays PU1 to PU5 have been completely released, and as soon as these relays have been released pickup relay PU6 also releases. It is to be noted that slow release relay 121, Fig. 3, remains energized so long as signals are being transmitted, thereby to hold positive battery from source 26b on conductor 29 for the operation of the transfer relays and Thyratron tubes. The release of relay 121, which occurs upon cessation of transmission for a period of time appreciably greater than that required for the transmitter distributor brush to pass two code segments, causes all the apparatus of the receiving distributor to be restored to normal, which means that Thyratron tube 45 is fired, and thereby effects synchronization and proper phasing of the receiving distributor. The radio system differs from the line wire system in the respect that normally tube 45 is firing, whereas in the line wire circuit tube 46 normally is firing when no signals are being received.

In certain types of grid-controlled gas-discharge tubes, the reapplication of plate battery to the tubes may cause the tubes to fire even though their grids are biased negatively at the time to prevent firing. To obviate this possibility, resistances 50, which in the circuit illustrated are of the order of one megohm each, are connected across the armatures 40 and associated make contacts of the transfer relays 31 to 36, and resistances 50' of the order of one-half megohm are connected across the armatures 28 and 141 and associated make contacts of battery supply relays 25 and 121, so that the plate circuits of the tubes are never completely opened.

Various modifications of the apparatus and circuit arrangements of the two specific embodiments shown, and various equivalents or substitutes for the devices illustrated, will readily occur to those versed in the art without departing from the spirit or scope of the present invention. The disclosure, therefore, is for the purpose of illustrating the principles of the invention, which is not to be regarded as limited except as indicated by the scope of the appended claims.

60. What is claimed is:

1. In a telegraph system in which permutation code signals are transmitted by marking and spacing pulses separated by intervals, a receiving distributor circuit responsive to said pulses comprising a plurality of gas-filled discharge tubes having control electrodes, relay means responsive to said marking and spacing pulses for applying a firing potential to the control electrodes of said tubes as the marking and spacing elements of each signal are received, transfer relays controlled by the anode circuits of said tubes for connecting said relay means to said tubes successively to cause the tubes to fire in predetermined order, and means controlled jointly by said relay means and said tubes for storing

13

the marking and spacing code elements of each character signal received.

2. In a telegraph system in which permutation code signals are transmitted by marking and spacing pulses separated by intervals, a receiving distributor circuit responsive to said pulses comprising a plurality of grid-controlled gas-filled discharge tubes having control electrodes, relay means responsive to said marking and spacing pulses for applying a firing potential to the control electrodes of said tubes as the marking and spacing elements of each signal are received, transfer relays controlled by the anode circuits of said tubes for connecting said relay means to said tubes successively to cause the tubes to fire in predetermined order, means controlled jointly by said relay means and said tubes for storing the marking and spacing code elements of each character signal received, a signal recording device and means for applying said stored signals to said recording device.

3. In a telegraph system in which permutation code signals are transmitted by polar marking and spacing pulses separated by intervals, a receiving distributor circuit responsive to said pulses comprising a plurality of gas-filled discharge tubes having control electrodes, means including a relay responsive to said marking pulses and a relay responsive to said spacing pulses for applying a firing potential to the control electrodes of said tubes as the marking and spacing elements of each signal are received, transfer relays controlled by the anode circuits of said tubes for connecting said relay means to said tubes successively to cause the tubes to fire in predetermined order, and relays controlled jointly by said relay means and said tubes for storing the marking and spacing code elements of each character signal received.

4. In a start-stop telegraph system in which permutation code signals are transmitted by marking and spacing pulses separated by intervals, a receiving distributor circuit responsive to said pulses comprising a plurality of gas-filled discharge tubes having control electrodes, relay means responsive to said marking and spacing pulses for applying a firing potential to the control electrodes of said tubes as the marking and spacing elements of each signal are received, transfer relays controlled by the anode circuits of said tubes for connecting said relay means to said tubes successively to cause the tubes to fire in predetermined order, means controlled jointly by said relay means and said tubes for storing the marking and spacing code elements of each character signal received, and means including at least one of said tubes and transfer relays and operative after a character signal has been received for conditioning the distributor circuit for the reception of the next character signal.

5. In a start-stop telegraph system in which permutation code signals are transmitted by marking and spacing pulses separated by intervals, a receiving distributor circuit responsive to said pulses comprising a plurality of gas-filled discharge tubes having control electrodes, relay means responsive to marking and spacing pulses for applying a firing potential to the control electrodes of said tubes as the marking and spacing elements of each signal are received, transfer relays controlled by the anode circuits of said tubes for connecting said relay means to said tubes successively to cause the tubes to fire in predetermined order, means controlled jointly by said relay means and said tubes for storing

14

the marking and spacing code elements of each character signal received, and means comprising at least one of said tubes and transfer relays and responsive to a marking pulse received subsequent to the reception of a character signal for conditioning the distributor circuit for the reception of the code elements of the next character signal.

6. In a start-stop telegraph system in which permutation code signals are transmitted by marking and spacing pulses separated by intervals, a receiving distributor circuit responsive to said pulses and a stop pulse comprising a plurality of gas-filled discharge tubes having control electrodes, relay means responsive to said marking and spacing pulses and said stop pulse for applying a firing potential to the control electrodes of said tubes as the marking and spacing elements of each signal are received, transfer relays controlled by the anode circuits of said tubes for connecting said relay means to said tubes successively to cause the tubes to fire in predetermined order, means controlled jointly by said relay means and said tubes for storing the marking and spacing code elements of each character signal received, and means comprising at least one of said tubes and transfer relays and responsive to a stop pulse for conditioning the distributor circuit for the reception of the code elements of the next character signal.

7. In a start-stop telegraph system in which permutation code signals are transmitted by marking and spacing pulses separated by intervals, a receiving distributor circuit responsive to said pulses comprising a plurality of gas-filled discharge tubes having control electrodes, relay means responsive to said marking and spacing pulses for applying a firing potential to the control electrodes of said tubes as the marking and spacing elements of each signal are received, transfer relays controlled by the anode circuits of said tubes for connecting said relay means to said tubes successively to cause the tubes to fire in predetermined order, means controlled jointly by said relay means and said tubes for storing the marking and spacing code elements of each character signal received, and means for maintaining one of said tubes fired during the interval following the reception of a character signal for conditioning the distributor circuit for the reception of the next character signal.

8. In a telegraph system in which permutation code signals are transmitted by marking and spacing pulses separated by intervals, a receiving distributor circuit responsive to said pulses comprising a plurality of grid-controlled gas-filled discharge tubes, a capacitative circuit and relay means responsive to said marking and spacing pulses for causing said capacitative circuit momentarily to apply a firing potential to said tubes as the marking and spacing elements of each signal are received, transfer relays controlled by the anode circuits of said tubes for connecting said relay means to said tubes successively to cause the tubes to fire in predetermined order, and relays controlled jointly by said relay means and said tubes for storing the marking and spacing code elements of each character signal received.

9. In a telegraph system in which permutation code signals are transmitted by marking and spacing pulses separated by intervals, a receiving distributor circuit responsive to said pulses comprising a plurality of grid-controlled gas-filled discharge tubes, means for normally main-

taining negative potential on the grids of said tubes to prevent firing of the tubes, means comprising a condenser and relay controlled means responsive to said pulses for causing said condenser momentarily to reduce the negative potential on the grids of certain of said tubes to cause firing thereof as the marking and spacing elements of each signal are received, transfer relays controlled by the anode circuits of said tubes for connecting said relay means and said condenser to certain of said tubes to cause the tubes to fire in predetermined order, and means controlled jointly by said relay means and said tubes for storing the marking and spacing code elements of each character signal received.

10. In a telegraph system in which permutation code signals are transmitted by marking and spacing pulses separated by intervals, a receiving distributor circuit responsive to said pulses comprising a plurality of grid-controlled gas-filled discharge tubes, means for normally maintaining negative potential on the grids of said tubes to prevent firing of the tubes, means comprising a condenser and relay controlled means responsive to said marking and spacing pulses for causing said condenser momentarily to apply a ground to the grid biasing circuits of certain of said tubes to cause firing thereof as the marking and spacing elements of each signal are received, transfer relays controlled by the anode circuits of said tubes for connecting said relay means and said condenser to certain of said tubes to cause the tubes to fire in predetermined order, and means controlled jointly by said relay means and said tubes for storing the marking and spacing code elements of each character signal received.

11. In a telegraph system in which permutation code signals are transmitted by marking and spacing pulses separated by intervals, a receiving distributor circuit responsive to said pulses comprising a plurality of gas-filled discharge tubes having control electrodes, relay means responsive to said marking and spacing pulses for applying a firing potential to the control electrodes of said tubes as the marking and spacing elements of each signal are received, transfer relays controlled by the anode circuits of said tubes for connecting said relay means to said tubes successively to cause the tubes to fire in predetermined order, means controlled jointly by said relay means and said tubes for storing the marking and spacing code elements of each character signal received, and means for synchronizing said receiving circuit with the signal transmitting source comprising a slow-acting relay for controlling the supply of energizing current for said tubes, said relay being effective to disable the tubes in response to a synchronizing signal.

12. In a telegraph system in which permutation code signals are transmitted by marking and spacing pulses separated by intervals, a receiving distributor circuit responsive to said pulses comprising a plurality of gas-filled discharge tubes having control electrodes, relay means responsive to said marking and spacing pulses for applying a firing potential to the control electrodes of said tubes as the marking and spacing elements of each signal are received, transfer relays controlled by the anode circuits of said tubes for connecting said relay means to said tubes successively to cause the tubes to fire in predetermined order, means controlled jointly

ly by said relay means and said tubes for storing the marking and spacing code elements of each character signal received, and means for synchronizing said receiving circuit with the signal transmitting source comprising a slow-release relay which when operated supplies energizing current for said tubes, said relay remaining unoperated to disable said tubes in response to a synchronizing signal.

13. In a start-stop telegraph system, a transmission line over which permutation code signals are transmitted by marking and spacing pulses separated by intervals, a receiving distributor circuit connected to said line and responsive to said pulses comprising a plurality of gas-filled discharge tubes having control electrodes, a first relay responsive to said marking and spacing pulses and a second relay responsive only to said marking pulses, said first relay applying a firing potential to the control electrodes of said tubes as the marking and spacing elements of each signal are received, transfer relays controlled by the anode circuits of said tubes for connecting said first relay to said tubes successively to cause the tubes to fire in predetermined order, and storage devices respectively for storing the marking and spacing code elements of each character signal received, said second relay controlling the operation of certain of said storage devices.

14. In a start-stop telegraph system, a transmission line over which permutation code signals are transmitted by marking and spacing pulses separated by intervals, a receiving distributor circuit connected to said line and responsive to said pulses comprising a plurality of gas-filled discharge tubes having control electrodes, a first relay responsive to said marking and spacing pulses and a second relay responsive only to said marking pulses, said first relay applying a firing potential to the control electrodes of said tubes as the marking and spacing elements of each signal are received, transfer relays controlled by the anode circuits of said tubes for connecting said first relay to said tubes successively to cause the tubes to fire in predetermined order, and storage devices respectively for storing the marking and spacing code elements of each character signal received, said second relay controlling the application of marking pulses to said storage devices.

15. In a telegraph system, means for transmitting a radio carrier which is modulated by different frequencies respectively representing marking and spacing pulses, means for receiving said radio signals comprising means for detecting and filtering out said marking and spacing pulses, a distributor circuit comprising a plurality of gas-filled discharge tubes having control electrodes, means comprising a relay responsive to said spacing pulses and a relay responsive to said marking pulses for applying a firing potential to the control electrodes of said tubes as the marking and spacing elements of each signal are received, transfer relays controlled by the anode circuits of said tubes for connecting said first named relays to said tubes successively to cause the tubes to fire in predetermined order, and means controlled jointly by said relays and said tubes for storing the marking and spacing code elements of each character signal received.
